UNITED STATES PATENT OFFICE.

DAVID W. HAWKSWORTH, OF DETROIT, MICHIGAN, ASSIGNOR TO HUTCHINS CAR ROOFING COMPANY, OF DETROIT, MICHIGAN, A CORPORATION OF MICHIGAN.

CAR-ROOF.

1,264,069.

Specification of Letters Patent. Patented Apr. 23, 1918.

Application filed February 19, 1914. Serial No. 819,619.

To all whom it may concern:

Be it known that I, DAVID W. HAWKSWORTH, a citizen of the United States of America, residing at Detroit, in the county 5 of Wayne and State of Michigan, have invented certain new and useful Improvements in Car-Roofs, of which the following is a specification, reference being had therein to the accompanying drawings.

10 The invention relates to car roofs of the all metallic type, and it is the object of the invention to obtain a relatively light construction, which is inexpensive to manufacture and is easily assembled.

15 In the drawings:

Figure 1 is a cross section through a portion of the roof adjacent to the eaves;

Fig. 2 is a section in the plane of the ridge;

20 Fig. 3 is a section on line y—y Fig. 1;

Figs. 4 and 5 are respectively a plan view and a side elevation of the securing means for the saddle-block and carline caps; and

Fig. 6 is a perspective view of the clip.

25 A are the carlines formed of beams of inverted T-section, and which extend from eave to eave. B are the side plates of the car frame, which are notched at C to receive the carline and have their upper edges in the plane of the roofing sheets and of a corresponding angle. D are purlins, preferably formed of channel beams in length to extend between the adjacent carlines, and having their ends E flattened and riveted to the 30 base flange of the carline. The top of these purlins are in the plane of the roofing sheets and are but a slight distance below the upper edge of the web of the carline. E' are the roofing sheets having inverted U-edge-flanges F, the flanges of the adjacent sheets being nested and arranged over the web of the carline.

To secure these sheets in position without interfering with the strength of the carline 45 and also to secure the saddle-blocks, I have provided a bolt-engaging clip G. This is preferably a forging having parallel side plates embracing the web of the carline and riveted or otherwise secured at H in the line 50 of the neutral axis of the beam. Above the web of the beam the clip is expanded in width and is cut away at J to form an entrance slot for the head K of the saddle-

securing bolt L. The shank of this bolt passes through a slot M in the top of the 55 clip and the shoulder of the head engages the underside of the clip, as shown. Thus a firm connection between the beam and the bolt is obtained without in any way weakening the former, as would be the case where 60 the top edge of the beam is cut away. The saddle-block N is secured in position by the bolt L and serves also to hold in position a cap O which embraces the nested flanges of the roofing sheets. This cap is provided 65 with laterally-extending foot-flanges P, which rest upon the sheet, and the cap is further secured down to the carline by a clamp arranged near the eaves. This clamp comprises a depending hook-bolt Q having a 70 shouldered head Q' engaging a boss R in the sheet and clamped thereto by a washer R' and a riveted head R². The depending hook is engaged with an inverted U-bolt S, which embraces the web of the beam and 75 passes through apertures in the base thereof, being provided with clamping nuts S' at its lower end.

With the construction described, the sheets may be easily assembled by laying them 80 upon the side plates B and purlins D. The caps O are then placed in position, the depending hooks Q being passed through slots O' in the nested flanges of the sheets and being laterally engaged with the U-bolts S. 85 The nuts S' are then tightened to draw the U-bolt downward, which securely clamps the sheets down upon the car-frame. The caps O are further held down by the saddle-blocks N, which in turn are secured by the 90 bolts L. Thus, without materially weakening the strength of the carline, the roofing sheets are securely held down, and this permits of using lighter beams for the carlines than with constructions where it is necessary to cut away the beams for the securing 95 means. The strength of the carline is not weakened materially since where the greatest stress occurs and where the saddle-blocks are secured to the carline the securing 100 means passes through the carline in its neutral axis, and since where the cap embracing the nested flanges of the roofing sheets is secured to the carline the stress upon the carline is materially less and the carline is over-size at this point. The carlines and the pur-

lins being arranged within the same vertical space limits the thickness of the roof is lessened, which increases the available space within the car.

5. To prevent danger of accidental disengagement of the bolt L, I preferably provide a gib T, which is inserted between the head of the bolt and the slotted side of the clip, and has its ends bent over at T' to prevent 10 disengagement.

What I claim as my invention is:—

15. 1. A car roof, comprising carlines of inverted-T cross section, roofing sheets having inverted-U edge-flanges in nested relation, embracing the web of the carline, caps embracing said nested flanges, and means for clamping said caps to the carlines comprising headed members and separate members attached to said carlines and connected with 20 said headed members.

25. 2. A car roof comprising a carline of inverted-T cross section, roofing sheets having weather-proofing flanges adjacent to said carline, a cap embracing said flanges, and means for clamping said cap to said carline comprising a pair of coöperating tie members detachably engaged with each other and respectively secured to said cap and carline.

30. 3. In a car roof, the combination with a carline of inverted-T cross section, of purlins connected to said carline within the vertical space limits thereof, roofing sheets supported upon said purlins having marginal weather-proofing flanges adjacent to 35 said carline, a cap embracing said flanges, a depending hook on said cap, and a loop for engaging said hook, vertically adjustably secured to said carline.

40. 4. In a car roof, the combination with a carline of inverted-T section, of roofing sheets having weather-proofing marginal flanges adjacent to said carline, a cap embracing said flanges, a U-bolt embracing the web of said carline and passing through 45 apertures in the base thereof, and a depending hook upon said cap for engaging said U-bolt above said carline.

50. 5. In a car roof, the combination with a carline of inverted-T cross section, of roofing sheets having marginal weather-proofing flanges adjacent to said carline, a cap for embracing said flanges, a depending hook secured to said cap above the web of said carline, a U-bolt embracing the web of said carline and engageable with said hook, the 55 lower ends of said bolt passing through apertures in the base flanges of said carline and being threaded, and clamping nuts for

engaging the threaded ends below said carline.

60. 6. In a car roof, the combination with a carline of inverted-T section, roofing sheets and a saddle-block, of a bolt for securing said saddle-block, having a head at its lower end, and a clip-plate secured to said carline near the neutral axis thereof, extending above the upper edge of the web, and laterally slotted to form a seat for the engagement of the head of said bolt.

65. 7. In a car roof, the combination with a carline of inverted-T section, of means for clamping a saddle-block thereto, comprising an inverted U-shaped clip embracing the web of the carline and secured thereto near the neutral axis thereof, the portion of said clip above said carline being provided with a laterally-extending T-slot, and a bolt having a head engageable with said slot and a shank projecting upward into engagement with the saddle-block.

70. 8. In a car roof, the combination with a carline of inverted-T section, of means for clamping a saddle-block thereto comprising an inverted U-shaped clip embracing the web of the carline and secured thereto near the neutral axis thereof, the portion of said clip above said carline being provided with a laterally-extending T-slot, a bolt having a head engageable with said slot and a shank projecting upward into engagement with the saddle-block, and a gib inserted between the head of said bolt and the slotted side of 85 the clip to lock said bolt from accidental disengagement.

80. 9. In a car roof, the combination with a carline of inverted-T section, and roofing sheets having nested flanges embracing the web of the carline, of a common means for attaching a saddle-bolt to said carline and for forming a support for said nested 90 flanges.

95. 10. In a car roof, the combination with a carline of inverted-T section and roofing sheets having nested flanges embracing the web of the carline, of a member embracing 105 said nested flanges, and a clip embracing the web portion of the carline having a recess for the bolt head and providing a support for said nested flanges.

In testimony whereof I affix my signature 110 in presence of two witnesses.

DAVID W. HAWKSWORTH.
